UNITED STATES PATENT OFFICE.

HARKEY M. MACOMBER, OF DOWNEY, AND HOMER H. PYRON, OF FULLERTON, CALIFORNIA.

DEVICE FOR USE IN CONNECTION WITH DRILLING TOOLS.

Application filed July 23, 1923. Serial No. 653,088.

To all whom it may concern:

Be it known that we, HARKEY, M. MACOMBER and HOMER H. PYRON, citizens of the United States, and residents of Downey, 5 county of Los Angeles, and Fullerton, county of Orange, State of California, have invented new and useful Improvements in Device for Use in Connection with Drilling Tools, of which the following is a specification.

10 This invention has to do with a device for use in connection with drilling tools, or the like, to facilitate lowering them into a hole.

15 In drilling wells with the rotary method the drilling tools, that is, the drill pipe, bits, etc., are frequently removed from the hole. The drilling tools being heavy are more or less difficult and dangerous to 20 handle, this being particularly true when the drill pipe is long. To facilitate lowering the tools into the hole valve devices have been applied to the tools to prevent fluid, standing in the hole, from entering and 25 flowing upwardly into the drill pipe. When tools are thus "floated" into the hole some fluid has to be pumped into the drill pipe from its upper end to prevent the pipe from collapsing due to the fluid pressure on the 30 exterior of the pipe. The valve devices heretofore used have been constructed so that they are normally held closed by a spring and are forced open when fluid is pumped downwardly in the drill pipe for 35 purpose of circulation.

It is an object of this invention to provide a simple, improved device applicable to drilling tools to prevent flow of fluid into the 40 drill pipe from the hole and to allow flow of fluid downwardly through the drill pipe and into the hole.

Another object of this invention is to provide a device of the character specified which operates to prevent flow of fluid upwardly into the drill pipe from the hole and which allows free flow of fluid downwardly through the drill pipe to discharge into the hole.

50 Another object of this invention is to provide a device of the character specified which is simple and reliable and which embodies no springs or like parts such as are liable to break or fail.

55 Another object of the invention is to provide a device of the character specified

with means whereby a certain amount of fluid may be allowed to enter the pipe from the hole so that it is unnecessary to pump fluid into the pipe to prevent collapsing.

It is another object of this invention to 60 provide a device of the character specified which operates automatically to prevent the flow of fluid into the pipe from the hole and allows free flow of fluid downwardly through the pipe, and which contains only 65 one moving part.

It is another object of this invention to 70 provide a device of the character specified that can be easily and quickly applied to ordinary drilling tools without altering or modifying them in any way.

It is another object of this invention to 75 provide a device of the character specified which can be assembled as a unit suitable for application to standard drilling tools without altering or modifying the tools in any way.

The various objects and features of our 80 invention will be best and more fully understood from the following detailed description of a typical preferred form of the invention, throughout which description reference is had to the accompanying drawings, in which:

Fig. 1 is a sectional view showing a well 85 with typical drilling tools being lowered into it, the drilling tools being provided with the device of the present invention;

Fig. 2 is an enlarged detail sectional view 90 of the drilling tools at the point where they are provided with the device of this invention, being a view taken as indicated by the line 2-2 on Fig. 1;

Fig. 3 is an enlarged detail transverse 95 sectional view of the device provided by our invention, being a view taken as indicated by the line 3-3 on Fig. 2; and

Fig. 4 is an enlarged detailed transverse 100 sectional view of the device provided by our invention, being a view taken as indicated by the line 4-4 on Fig. 2.

In the drawings numeral 10 designates a well, and numeral 11 designates a casing set in the well in the usual manner. In Fig. 1 of the drawings we have illustrated a typical bit 12 being lowered into the well through the casing 11 on a string of drill pipe 13. The drill pipe 13, in accordance with standard practice, includes a plurality of sections 14 of pipe, joined by suitable 110

couplings 15, to form stands which are joined by suitable tool joints 16. In handling the drill pipe it is usually separated or disconnected only at the tool joints 16. In 5 the drawings we have illustrated an ordinary or standard tool joint, comprising a male section "A", and a female section "B". The male section "A" is formed in its upper end with a screw threaded socket 17 to receive the end of a section 14 of drill pipe, while the lower end of the female section "B" is formed with a screw threaded socket 18 to receive the upper end of a section 14 of drill pipe. On the lower end of section 15 "A" there is a large tapered projection or pin 19 adapted to screw thread into a correspondingly tapered socket 20 in the upper end of the section "B". The threads of the pin 19 and socket 20 are preferably coarse 20 and such as to allow the two sections to be screwed tightly together, as we have clearly illustrated in Fig. 2. In accordance with standard practice the sections "A" and "B" of the joint have openings 22 extending 25 longitudinally through them to conduct fluid between the joined sections of drill pipe.

For the purpose of this invention we will 30 use the term "drilling tools", to designate the drill pipe, the couplings, the tool joints connecting the stands of drill pipe, the bit 12, or any like or similar parts that may correspond or be equivalent to these parts.

The device provided by our invention 35 may be applied to the drilling tools in various manners, it being particularly suited, however, for application to the tools at a tool joint 16, or like point. In order to illustrate and make clear a typical application of our invention we will herein describe it applied to or at a tool joint 16, it being understood, however, that we do not intend such description to be construed as limiting the invention to this or any other such 40 specific application.

The device provided by our invention includes, generally, two parts, a valve member 25, and a seat 26 for the valve member 25. The seat 26 may be provided on a ring 27, applied or mounted in a drilling tool, for instance, a section of a tool joint, so that it passes any fluid that may flow through the drill pipe. The valve member 25 is, in 45 accordance with our invention, arranged below the seat 26, so that it is movable vertically into and out of cooperative engagement with the seat. The valve member 25 is free, being entirely disconnected from any other part. In the form of the invention illustrated in the drawings, the valve member 25 is in the form of a ball, of such size as to fit in the drilling tool with substantial clearance and yet be caught and 55 carried by flow of fluid through the tool. In practice we prefer to make the ball

hollow so that it is comparatively light and, therefore, readily moved by the flow of fluid through the tool. When the valve member is in the form of a ball the seat 26 is, of course, ground or otherwise finished 70 to receive it so that it will operate to effectively close the opening through the ring when in engagement with the seat.

We provide means 35 for retaining the valve member 25 in position so that it will 75 properly cooperate with the seat 26. This retaining means may include a bar 28, or the like, arranged transversely in the drilling tool at a point spaced somewhat below the valve seat so that it will prevent the valve 80 from dropping downwardly too far in the tool or drill pipe.

In accordance with the preferred form of our invention we provide a carrier 30 which includes a body 31 to carry the ring 27, 85 valve part 25 and retaining means for the valve member, and a flange 32 for supporting the body in a drilling tool. The body 31 may be in the form of a cylinder, of such size as to slidably fit into one of the drilling parts, for instance, into the opening 22 in one of the sections of the tool joint. In practice the ring 27 may be formed integral with the body 31 or it may be 90 screw threaded into the body, as we have illustrated in the drawings. When the body 31 is to be arranged in the upper or male section "A" of a tool joint the ring 27 is preferably screw threaded into the body so that it is removable from the lower end of 95 the body. When the valve member 25 is in the form of a ball, completely detached from any other part, it may be freely carried in the body 31 between the ring 27 and retaining means 35.

When the device is provided with the carrier 30 the retaining means 35 may be carried by the body of the carrier, as we have illustrated in the drawings. The particular retaining means illustrated in the drawings includes two retaining bars 28 arranged transversely of each other and carried by a ring 36 mounted in the lower part of the body 31. The ring 36 is preferably screw threaded into the lower end of the body 31 so that it can be removed to allow for removal of the valve member 25 and seat ring 27. 100

The flange 32 is provided on the body 31 of the carrier to engage or cooperate with a tool part or parts, so that it holds the body in the desired position. In the form of the invention illustrated in the drawings the flange 32 is an annular flange, formed at one end of the body, in the present case at the upper end of the body, and projects from the body in a manner to be held between two adjacent tool parts. In the drawings we have illustrated the flange 32 confined or held in place between the lower end 105 of the pipe section carried in the socket 110 115 120 125 130 135 140 145 150 155 160 165 170 175 and a shoulder 38 in the joint section "A" at the inner end of the socket 17. If it is desired to mount the body of the carrier in the drill pipe section rather than in the section of the tool joint the flange 32 may be provided at the lower end of the body so that the body projects upwardly from it instead of downwardly. This arrangement allows the body to be made larger as the opening in the drill pipe section is larger than the opening in the tool joint section.

In accordance with our invention we may provide the device with means for allowing a certain amount of fluid to pass upwardly through the device and into the drill pipe when the valve is closed so that it will be unnecessary to pump fluid downwardly into the drill pipe to prevent collapsing. This means may include by-pass openings 40 in the ring 27 to allow flow of fluid through the ring, although the valve member is in engagement with the seat. The by-pass openings 40 may be closed by plugs 42 when it is not desired to have flow into the drill pipe when the valve member is seated. By providing a plurality of by-pass openings 40 the required amount of flow upwardly past the device can be had by opening the proper number of openings and the flow is not entirely cut off in the event that one of the several openings in operation becomes clogged.

In using our invention it may be embedded or constructed permanently in a suitable drilling tool, or it may, as we have above described, be constructed as a unit, suitable for application to ordinary or standard drilling tools without alteration or modification of the tool. With the form of the invention we have above described the carrier 30 is arranged in the desired tool joint section "A" with the flange in engagement with the shoulder 38 at the time this tool joint section is screw threaded onto the pipe section 14. When the tool joint section is made tight on the pipe section the device of our invention is solidly and securely held in place ready for operation. The tool joint section to which the device is applied may be at the lower end of the drill pipe, or it may be at any other point that the operator may desire. With the device thus applied to a tool joint section the drill pipe is handled in exactly the same manner as it ordinarily is, that is, the stands may be assembled and disconnected in the usual manner without reference to or interference with the device. When a drill pipe is being lowered into a hole with the device of our invention at or near its lower end the fluid from the hole, tending to flow upwardly into the drill pipe, will carry the valve member 25 into seated engagement with the seat 26 and will hold it in this position so that the pipe is floated into the hole. If one or

more of the by-pass openings 40 are opened there will be a certain amount of flow of fluid upwardly into the drill pipe past the device so that it will be unnecessary for the operator to fill fluid into the drill pipe to prevent collapsing. When the drill pipe has been lowered into position and fluid is pumped downwardly into the drill pipe to establish circulation the valve member 25 drops away from the seat 26 opening the passage through the device so that the flow of fluid is not in any way restricted. With the device constructed as we have herein set forth it can be repaired, that is, the retaining means, the valve member, or the ring 27, can be removed for the purpose of replacement or repair through the lower end of the body 13, without removing the tool joint section from the drill pipe.

Having described only a typical preferred form of our invention we do not wish to limit ourselves to the specific details hereinabove set forth but wish to reserve to ourselves any changes or variations that may appear to those skilled in the art or fall within the scope of the following claims.

Having described our invention, we claim:

1. In combination with drilling tools, a seat in the tools, a valve member to cooperate with the seat to prevent flow of fluid upwardly through the tools, and means for allowing some flow upwardly in the tools when the valve member is in cooperative engagement with the seat.

2. In combination with drilling tools having a fluid passage through them, a seat in the passage, a valve cooperating with the seat to close the passage only against upward flow in the passage, means for allowing some flow of fluid upwardly in the tools when the valve is cooperating with the seat to close the passage, and means for regulating said first mentioned means.

3. In combination with drilling tools having an opening through them, a seat ring mounted in the opening, the ring having a main opening and a by-pass opening through it, and a free valve member retained in the opening below the ring to be moved into cooperative engagement with the seat to close the said main opening by upward flow of fluid in the opening.

4. In combination with drilling tools having an opening through them, a seat ring mounted in the opening, the ring having a main opening and a by-pass opening through it, means for closing the by-pass opening, and a free valve member retained in the opening below the ring to be moved into cooperative engagement with the seat to close the said main opening by upward flow of fluid in the opening.

5. A device to be applied to the fluid passage of drilling tools including, a carrier to be arranged in the passage, a flange on

the carrier to be held between adjacent tool parts to secure the carrier in place, a seat in the carrier, and a valve freely carried in the carrier below the seat to be moved 5 into cooperative engagement with the seat by upward flow in the passage.

6. A device to be applied to the fluid passage of a tool joint section including, a carrier to be arranged in the passage, 10 means for securing the carrier in the passage, and a valve device operable to prevent upward flow of fluid through the passage removable from the carrier through the end of the passage.

15 7. A device to be applied to the fluid

passage of a tool joint section including, a carrier to be arranged in the passage, a flange extending from the carrier to be held between a part of the tool joint section and a part connected to the tool joint section, 20 and a valve device operable to prevent upward flow of fluid through the passage removable from the carrier through the end of the passage.

In witness that we claim the foregoing 25 we have hereunto subscribed our names this 13th day of July 1923.

HARKEY M. MACOMBER.
